UNITED STATES PATENT OFFICE.

HIRAM H. SHELTERS, OF BURLINGTON, VERMONT.

TIMER.

1,313,561,

Specification of Letters Patent.

Patented Aug. 19, 1919.

Application filed March 28, 1918. Serial No. 225,292.

To all whom it may concern:

Be it known that I, HIRAM H. SHELTERS, a citizen of the United States, residing at Burlington, in the county of Chittenden and State of Vermont, have invented certain new and useful Improvements in Timers; and I declare the following to be a full, clear, and exact description of the invention, such as will enable others skilled in the art 10 to which it appertains to make and use the same.

This invention relates to timers, and it more specifically relates to an improved removable attachment for a timer of known construction.

One of the objects of this invention is to provide certain improvements on the well known Ford timer, which enables the contact-race and carbon or other brush to be 20 quickly and easily removed and replaced by other elements of their kind without the use of any tool.

Another object is to provide a device of this character in which the contacts which 25 coöperate with the carbon also provide securing means whereby a set of spring clamps is permanently secured to the race so that the race and contacts and spring clamps constitute a unitary member which may be 30 quickly clamped to the original insulating ring of the timer and in closed circuit with the original contact elements of a Ford timer.

Another object is to provide a device of 35 this character which consists of few and simple parts and may be manufactured at the minimum expense.

Another object is to provide a device of this character which is strong, durable, 40 highly efficient, convenient and thoroughly practical.

Other objects and advantages may become apparent to persons who read the following details of description in connection 45 with the accompanying drawing in which—

Figure 1 is a central sectional view through a portion of a Ford timer in which parts have been removed and substituted by my improved timer mechanism;

50 Fig. 2 is a sectional view taken along the line 2—2 of Fig. 1;

Fig. 3 is a sectional view taken along the line 3—3 of Fig. 1;

Fig. 4 is an end elevation of an improved brush holder;

Fig. 5 is a side elevation of the brush holder shown in Fig. 4, parts being broken out to more clearly disclose its construction; and,

Fig. 6 is a sectional view taken along the line 6—6 of Fig. 5.

Referring to these drawings in detail, in which similar reference characters correspond with similar parts throughout the several views, the cam-shaft 10, the casing 11, the insulating race or ring 12, contact elements 13, and insulating washers 14 are of previously known construction, and are not, therefore, described in detail.

A carbon-brush 15 is supported within a 70 chamber 16 of the brush holder which is generally indicated by the numeral 17 in Figs. 4, 5 and 6. This brush holder is provided with a cylindrical chamber or aperture 18 through which a reduced end portion of the shaft 10 extends. The cylindrical portion 18 is recessed at 19 for receiving the end portion of a pin 20 which extends through the shaft 10 so as to prevent rotation of the member 17 with relation to 80 the shaft. A washer 21 is provided with an annular flange which fits over the ends of the pin 20 and prevents accidental removal or displacement of the latter. A nut 22 is in screw-threaded engagement with the 85 shaft 10 and coöperates with the elements 20 and 21 for effectually locking the member 17 on the shaft.

The carbon holder is preferably formed 90 of sheet metal being stamped from a flat blank (not shown) and then formed as shown in Figs. 4 and 5, a tongue 23 being struck up and turned inwardly of the chamber 16 so as to provide a seat against which a spring 24 is seated. The spring 24 normally presses the carbon 15 against a race 25 or against one of the contacts 26 of a series that extends through the race 25. The race 25 is of insulating material, whereas the contact elements 26 are of conducting 100 material.

For the purpose of removably securing the

race and its contact elements within the casing 11, I provide a set of spring clamping elements 27 each formed of conducting material. The elements 27 are previously 5 formed from sheet metal and each has one end secured to the race 25 by means of one of the contact elements 26 as clearly shown in Fig. 1. The other end of each element 27 is substantially 3-shaped or formed with 10 two clamping jaws 28 and 29 and a contact element 30 between the clamping jaws. The dual effect of each spring 27 is to press the contact element 30 into closed circuit with one of the contact elements 13 and to 15 clamp the insulating ring 12 with its jaws 28 and 29. However, when it is desired to renew the race 25 or the carbon 15, the manipulative elements 31 which are formed at the extremities of the elements 27 may be 20 pressed toward the center of the casing so as to disengage the insulating ring 12; and the elements 25, 26 and 27 may then be removed as a unitary member, and such member or a similar one may then be placed and clamped within the casing 11 by pressing the springs inward until they are in position to move outward into position for clamping the insulating ring 12.

From the foregoing description, it will be 30 seen that I have provided a timer mechanism which may be renewed without the necessity of renewing the more expensive parts of the timer. Although I have described this embodiment of my invention very specifically, it is not intended to limit the invention to these exact details, but I contemplate making minor changes within the scope of the inventive idea disclosed in the foregoing description and appended claims.

40 What I claim is:—

1. In a timer, the combination with a set of contact elements, of a second set of contact elements, a brush movable to close circuit alternately with said second contact elements, and a set of clamping elements of conducting material each removably secured by its inherent clamping effect to a contact element of one of said sets, each of said clamping elements being electrically connected to one of the contact elements of the other of said sets.
2. In a timer, the combination with a set of contact elements, an insulating ring in which said contact elements are mounted, 55 a second set of contact elements, an insulating race in which the second set of contact elements is mounted, a set of clamping elements of conducting material each permanently fixed with relation to said race and 60 removably secured by its inherent clamping effect to the said ring and being normally in electrical connection with one of the contact elements of each of said sets, and a brush coöperative with said race and with 65 the contact elements mounted therein.

3. In a timer, the combination with a set of contact elements, an insulating ring in which said contact elements are mounted, a second set of contact elements, an insulating race in which the second set of contact elements is mounted, a set of spring connecting elements of conducting material each permanently secured to said race and in closed circuit with one of the contact elements of the second said set, each of said spring connecting elements being normally held by its spring action removably in engagement with one of the contact elements of the second said set.

4. In a timer comprising a casing, an insulating element in the casing, and a set of contact elements extending through said insulating element and casing, the combination of an insulating race, a set of spring clamping elements of conducting material normally and removably clamped on the said insulating ring and thereby held in closed circuit with said contact elements, a second set of contact elements each in circuit with one of said clamping elements, and a brush coöperative with said race and the said second set of contact elements.

5. In a timer comprising a casing, an insulating element in the casing, and a set of contact elements extending through said insulating element and casing, the combination of an insulating race, a set of spring clamping elements of conducting material normally and removably clamped on the said insulating ring and thereby held in closed circuit with said contact elements, a second set of contact elements each in circuit with one of said clamping elements, and permanently securing it to said race so that said insulating race and spring clamping elements constitute a unitary member that may be detached and replaced by another member of its kind without the use of any tool, and a brush coöperative with said race and the second set of contact elements.

6. A timer brush holder formed of a single blank of sheet material having one end bent about a central line to form a tubular shaft-embracing portion, the opposite end of the blank being bent about a central line parallel to the first said central line so as to form a tubular brush receiving portion, a tongue being struck up from the blank and extending into the interior of said brush receiving portion so as to form a seat for a spring, a brush held by the receiving portion, and a compression spring seated in said brush securing portion between said tongue and brush.

7. A timer brush holder formed of a single blank of sheet material having one end bent about a central line to form a tubular shaft-embracing portion, the opposite side of the blank being bent about a central line parallel to the first said central line so

as to form a tubular brush-receiving portion, a tongue being struck up from the blank and extending into the interior of said brush-receiving portion so as to form 5 a seat for a spring to act against a brush when said brush is held by the brush-receiving portion.

In testimony whereof I have hereunto set my hand in the presence of two subscribing witnesses.
